US0D1060585S

(12) **United States Design Patent** (10) **Patent No.:** **US D1,060,585 S**
(45) **Date of Patent:** **** Feb. 4, 2025**

(54) **MINI COMPOUND BOW**

(71) Applicant: **Zhengzhou Black Sail Trading Co., Ltd.**, Zhengzhou (CN)

(72) Inventor: **Zhiqiang Zheng**, Zhoukou (CN)

(73) Assignee: **Zhengzhou Black Sail Trading Co., Ltd.**, Zhengzhou (CN)

(**) Term: **15 Years**

(21) Appl. No.: **29/965,754**

(22) Filed: **Sep. 29, 2024**

(51) LOC (15) Cl. **22-01**

(52) U.S. Cl.

USPC **D22/107; D21/571**

(58) **Field of Classification Search**

USPC D22/106, 107, 100; D21/570, 571, 572, D21/573

CPC F41B 5/10; F41B 5/105; F41B 5/1403

See application file for complete search history.

(57) **CLAIM**

The ornamental design for a mini compound bow, as shown and described.

DESCRIPTION

FIG. 1 is a front perspective view of a mini compound bow, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the mini compound bow, which form no part of the claimed design.

1 Claim, 8 Drawing Sheets
